Term of patent 14 years

(Cl. D22—3)

FIG. 1.

FIG. 2.

FIG. 3.

FIG. 4.

To all whom it may concern:

Be it known that I, Wallace O. Bassford, a citizen of the United States and a resident of the city of New York, in the county of New York and State of New York, have invented a new, original, and ornamental Design for an Electric Shaver, of which the following is a specification, reference being had to the accompanying drawing, forming a part thereof.

Fig. 1 is a side view of an electric shaver showing my new design;

Fig. 2 is an end view thereof,

Fig. 3 is a perspective view thereof showing the end opposite that shown in Fig. 2, and

Fig. 4 is a bottom view thereof.

The essential features of my design reside in the portion shown in solid lines on the drawing.

I claim:

The ornamental design for an electric shaver, substantially as shown and described.
